UNITED STATES PATENT OFFICE.

GEORGE W. ROBINSON, OF SAN DIEGO, CALIFORNIA, ASSIGNOR OF ONE-HALF TO F. N. DORLAND, OF SAN DIEGO, CALIFORNIA.

PISTON.

Application filed July 15, 1925. Serial No. 43,826.

My invention relates to pistons for internal combustion engines and a purpose of my invention is the provision of an expansible piston in which is incorporated means by which it can be positively expanded to effect an increase in its diameter so that when wear occurs either upon the peripheral surface of the piston or upon the wall of its cylinder, the resulting clearance is eliminated and a close running fit between piston and cylinder maintained at all times, thereby entirely eliminating what is generally known as piston slap, as well as greatly prolonging the life of the piston rings, ring grooves, wrist pins and cylinder walls, whereby maximum working efficiency and long life of the engine will be insured.

Another purpose of my invention is the provision of an expanding element which is capable of being adjusted so as to effect an expansion of the skirt without removal of the piston from its cylinder, the expanding element being in the form of a cam which can be adjusted to expand the skirt at the thrust or working side of the piston so that when adjustment of the skirt is effected the ring lands of the piston will be held clear of the cylinder wall and the piston maintained in perfect alinement. I will describe only four forms of piston embodying my invention and will then point out the novel features thereof in claims.

In the accompanying drawings

Figure 1 is a view in longitudinal vertical section of one form of piston embodying my invention.

Figure 2 is a view in longitudinal vertical section taken on the line 2—2 of Figure 1 looking in the direction of the arrows.

Figure 3 is a horizontal sectional view taken on the line 3—3 of Figure 1 and looking in the direction of the arrows.

Figure 4 is a fragmentary horizontal sectional view taken on the line 4—4 of Figure 1 looking in the direction of the arrows.

Figure 5 is a longitudinal vertical sectional view illustrating another form of piston embodying my invention.

Figure 6 is a longitudinal vertical sectional view taken on the line 6—6 of Figure 5 and looking in the direction of the arrows.

Figure 7 is a view in side elevation looking in the direction of the arrows 7—7 of Figure 5.

Figure 8 is a longitudinal vertical sec-

tional view of still another form of piston embodying my invention.

Figure 9 is a longitudinal vertical sectional view taken on the line 9—9 of Figure 8.

Figure 10 is a longitudinal vertical sectional view of a further form of piston embodying my invention.

Figure 11 is a longitudinal vertical sectional view taken on the line 11—11 of Figure 8 and looking in the direction of the arrows.

Figure 12 is a fragmentary view in side elevation of the piston embodied in the two preceding views.

Referring specifically to the drawings in which similar reference characters refer to similar parts in each of the several views and particularly to Figures 1 to 4, inclusive, I have herein shown a piston formed of an integral body of suitable metal to provide a head H from which extends a tubular body or skirt S, the piston having the usual annular grooves and journals for the packing rings and wrist pin (not shown) respectively.

The skirt S is slotted longitudinally at diametrically opposite points as indicated at 15 and 16, and the inner ends of the slots communicate with relatively wide slots 17 and 18 extending circumferentially of the skirt. Other slots 19 extend longitudinally of the skirt from the opposite ends of the slot 17 towards the free end of the skirt and terminate in relatively short transverse slots 20, so as to divide the skirt into a pair of expansible sections E and E'.

The sections E and E' are adapted to be expanded interiorly at the upper end of the slot 15 through the medium of a movable expanding element A having a cam surface 21 co-acting with a cam surface 22 formed on a stationary abutment member B. The element A is adapted to be moved longitudinally of the skirt so as to cause sliding move-

ment of its cam surface 21 over the cam surface of the member B with a corresponding expansion of the sections E and E', by means of a feeding member in the form of a shaft 23 journaled in bearings 24 and 25 formed

integral with the skirt S, the latter bearing being divided longitudinally by the slot 15 and having a tapered bore 25a. The shaft 23 is reduced in diameter as indicated at 26 and its reduced portion extends freely

through a sleeve 27 formed upon the expanding element A and then into the journal 24. The body portion 28 of the shaft is of tapered form to provide a cam adapted to engage the bore 25^a and is threaded at 29 to receive a feed nut 30 having a flattened surface 31 engaging the inner wall of the skirt S so as to prevent rotation of the nut, while its free end is reduced and threaded as indicated at 32 to receive a lock nut 33 having a washer 34. The shaft 23 is also provided with a kerf 35 so that a screw driver (not shown) may be readily inserted from the open end of the skirt and the shaft rotated as desired.

The stationary abutment member B is of L-shaped form with its vertical arm 36 provided with the cam surface 22 and its horizontal arm 37 extending inwardly and perforated to receive a reduced portion 26 of the shaft 23, the shaft co-operating with a lip 38 formed on the element and extending into the slot 17, to maintain the element in fixed position with its vertical arm 36 engaging the inner surface of the skirt S in overlying relation to the slot 15.

In practice, the sleeve 27 of the element A abuts the shoulder formed between the portions 26 and 28 of the shaft 23, and the feed nut 30 abuts the upper end of the bearing 25, so that when the shaft is rotated in a clockwise direction it will be fed upwardly through the nut 30 thus causing its tapered body portion 28 to spread the lower portion of the expandable sections E and E', while the expanding element A will be forced upwardly so as to engage the cam surface 22, whereby an outward pressure will be exerted against the upper portion of the sections, the body portion 28 and element A co-operating to evenly expand the sections along the length of the longitudinal slot 15.

Referring specifically to Figures 5 to 7, inclusive, I have herein shown an embodiment of my invention in which the skirt S is slotted longitudinally at 39 with the inner end of the slot communicating with a transverse slot 40 from the ends of which extend oppositely diverging slots 41. Diametrically opposite to the slot 40 is a transverse slot 42 from one end of which extends diagonally a slot 43 to the free end of the skirt. By slotting the skirt in this manner a pair of expandable sections are formed which are adapted to be expanded at the slot 39 by means of an expanding element in the form of a shaft 44 journaled in a two part bearing 45 provided with a tapered bore to receive the tapered body portion 46 of the shaft. Threaded shanks 47 and 48 are formed at opposite ends of the body portion 46 and project from the ends of the bearing 45 so as to receive respectively a stationary feed nut 49 and a lock nut 50 having a washer 51. It will be clear that by rotating

the shaft so as to cause its upward movement through the feed nut 49 the parts of the bearing 45 will be spread under the action of the tapered body 46 and the sections of the skirt thus expanded.

In Figures 8 and 9, I have shown another embodiment of my invention in which the skirt of the piston is slotted longitudinally at 52 and transversely at 53, with the ends of the slot 53 communicating with relatively short diagonal slots 54 diverging from each other towards the free end of the skirt, and terminating at circular openings 55 which latter function to prevent fracturing of the skirt beyond the slot. By this arrangement of slots the skirt is adapted to be expanded at spaced points along the length of the slot 52 by means of a pair of expanding elements in the form of wedge shaped blocks, 56 and 57, the former having a threaded opening 58 extending therethrough to receive the threaded portion 59 of a shaft 60 journaled in a two part bearing 61 formed integral with the skirt of the piston near the free end of the slot 52. One side of the block 56 engages a cam surface 62 formed on an L-shaped abutment 63 cast integral with the skirt of the piston above the transverse slot 53, and the opposite side of the block engages a cam surface 64 formed on a projection 65 cast integral with the skirt and divided longitudinally by the slot 52. The block 57 abuts a flange 66 formed upon the shaft 60 with its opposite sides engaging cam surfaces 67 and 68 formed on the confronting sides of the bearing 61. The shaft 60 is threaded at 59 in an opposed direction to the threaded portion 58 so as to receive a stationary feed nut 69 which abuts the upper end of the journal 61, while at the opposite end of the journal, a lock nut 70 and a washer 71 are provided.

It will be clear that with a screw driver applied to a kerf 72 formed in the end of the shaft 61, rotation of the shaft in one direction will cause it to move upwardly through the feed nut 69, thus imparting upward movement to the block 57 through the medium of the flange 66 so as to cause the block to engage the cam surfaces 67 and 68 and thus effect expansion of the lower portion of the skirt, while at the same time the block 56 is moved upwardly due to the opposed direction of its threads with respect to those of the feed nut 69 to cause expansion of the upper portion of the skirt outwardly from the cam surface of the abutment 63, whereby an even expansion of the skirt will be effected along the length of the slot 52.

In the form shown in Figures 10 to 12, inclusive, the skirt of the piston is slotted in the same manner as in the preceding form and is adapted to be expanded at spaced points along the length of its longitudinal

slot by means of a pair of expanding elements 73 and 74, the former having a threaded opening extending therethrough to receive the threaded portion 75 of a shaft 77 provided with a reduced upper end 78 journaled in a bearing 79 and with its lower end journaled in a two part bearing 80. The expanding element 74 abuts a flange 81 formed on the shaft 77 and projects into the longitudinal slot of the skirt in the form of a wedge adapted to engage cam surface 82 formed in the walls of the slot, while the expanding element 73 is provided with a cam surface 83 adapted to engage corresponding cam surfaces formed on projections 84 at either side of the slot. The body portion 76 of the shaft 77 is threaded oppositely to the portion 75 to receive a stationary feed nut 85 and a lock nut 86, and it will be clear that by rotating the shaft in a clockwise direction its upward movement through the feed nut 85 will cause upward sliding movements of the expanding elements 73 and 74 over their co-acting cam surfaces and thus effect an even expansion of the skirt along the length of its longitudinal slot.

It will be noted that in all the forms of my pistons their skirts are split at two spaced points to their free edges, and that an expanding element or elements is provided at one only of the points so that the skirts can be expanded to effect a snug fit of the pistons in their cylinders when cold and yet are free to constrict at the other of said points when heated, thus positively preventing freezing or sticking of the pistons in their cylinders. By this arrangement of slots and expanding elements the original adjustment is maintained for when the piston again cools the constricted skirt returns to its original diameter due to the inherent flexibility of the metal of which it is constructed.

From the foregoing description, it will be manifest that I have provided simple and durable means by which the split skirt of a piston can be adjusted to effect an expansion of the skirt when worn, thereby obviating the necessity of replacing a slightly worn piston with a new one, and greatly extending the time at which a reborning of the cylinder will be required.

Although I have herein shown and described only four forms of pistons embodying my invention, it is to be understood that various changes and modifications may be made therein without departing from the spirit of the invention and the spirit and scope of the appended claims.

60 What I claim is:

1. A piston comprising a hollow body formed to provide a head having a skirt slotted longitudinally and transversely to provide a pair of expansible sections, journals formed interiorly of the skirt, one of

said journals being split and having a tapered bore, a feeding member comprising a shaft rotatable in said journals and having a tapered and threaded body portion adapted to engage said tapered bore, and provided with a reduced portion, a stationary feed nut threadedly engaging said body portion, a stationary abutment element overlying one of said longitudinal slots and having a cam surface, and an expanding element mounted on said reduced portion and adapted to be engaged by said body portion, said element having a cam surface movable over the cam surface of said abutment when said shaft is rotated, whereby said abutment element and said body portion will function to expand said sections at spaced points and thus increase the diameter of the skirt.

2. A piston comprising a head having a slotted skirt, a feeding member comprising a shaft rotatably mounted on said skirt, means for imparting longitudinal movement to said shaft when rotated, and expanding elements arranged at spaced points upon said shaft and movable therewith in a manner to effect an expansion of said skirt when said shaft is rotated.

3. A piston comprising a head having a skirt provided at one side with intercommunicating slots arranged to provide a longitudinal slot extending to the free edge of the skirt, a transverse slot at the inner end of said longitudinal slot, and diverging slots extending from the ends of said transverse slot, said skirt slotted at the opposite side to provide a transverse slot, and a diagonal slot communicating therewith and extending to the free edge of the skirt, a journal formed integral with the skirt and divided by said longitudinal slot, said journal having a tapered bore, a shaft having a tapered body portion engaging said bore, threaded shanks on the ends of said body portion, a feed nut threaded on one of said shanks, and a lock nut threaded on the other of said shanks.

4. A piston comprising a head having a skirt provided with a longitudinal slot extending to its free end, a transverse slot communicating with the inner end of said first slot, diverging slots extending from said transverse slot towards the free end of said skirt and having enlarged ends, a journal formed integral with said skirt divided longitudinally by said first slot and having cam surfaces, an L-shaped abutment member formed integral with said skirt and having a cam surface, a projection formed on the skirt and having a cam surface, a shaft mounted in said journal and having oppositely threaded portions, a shoulder formed on said shaft, an expanding element threaded on one portion of said shaft and having cam surfaces adapted to engage the cam surfaces of said abutment and skirt, a second

expanding element threaded on the other portion of said shaft and having cam surfaces adapted to engage the cam surfaces of said journal, a stationary feed nut threadedly engaging said shaft for imparting longitudinal movement to said shaft when rotated, and a lock nut threaded on said shaft for locking the latter against movement.

5. A piston comprising a head having an integral slotted skirt provided with cam surfaces at spaced points along its length, expanding elements mounted for movement in said skirt, and means for imparting movement to said elements to cause the latter to engage said cam surfaces and thereby effect an increase in the diameter of the skirt uniformly along its length.

6. A piston comprising a head having a skirt slotted longitudinally at spaced points,

and means for expanding the skirt at one only of said points to effect a snug fit of the piston in its cylinder when cold, whereby said skirt is free to constrict at the other of said points when the piston is heated to thereby prevent freezing of the piston in its cylinder.

7. A piston having its skirt split at at least two points spaced circumferentially from each other to provide a pair of relatively expandible sections, and means for expanding the sections at one of the points for effecting a snug fit of the piston in its cylinder when cold, said sections being free to constrict at the other of said points when the piston is heated, to thereby prevent sticking of the piston in its cylinder.

GEORGE W. ROBINSON.
